UNITED STATES PATENT OFFICE.

MAURICE F. LINQUIST, OF NEW HAVEN, CONNECTICUT.

CORSET.

SPECIFICATION forming part of Letters Patent No. 280,638, dated July 3, 1883.

Application filed March 30, 1883. (No model.)

To all whom it may concern:

Be it known that I, MAURICE F. LINQUIST, of New Haven, in the county of New Haven and State of Connecticut, have invented a new and useful improvement in Corsets; and I do hereby declare the following, when taken in connection with the accompanying drawings and the letters of reference marked thereon, to be a full, clear, and exact description of the same, and which said drawings constitute part of this specification, and represent, in—

Figure 1, a rear view of the corset; Fig. 2, a rear view of the spinal stay detached; Fig. 3, an end view of the same; Fig. 4, a transverse section of the corset through the back-stay; Fig. 5, a perspective view of the shoulder brace or spring detached.

This invention relates to an improvement in corsets, the object being to construct the corset so as to serve as a spinal and shoulder supporter; and it consists in the construction as hereinafter described, and more particularly recited in the claims.

The back-stay is composed of two steel or other suitable springs, *a a*, (the stay shown detached in Fig. 2,) arranged substantially parallel with each other and distant from each other so as to lie comfortably at each side of the spine—say about one inch apart. These springs are connected by transverse metal connections *b*, more or less in number, the said connections bent outward, as seen in Fig. 3, so as to give a clear recess, *d*, between the springs *a a* for the spine. This stay is arranged in the corset in a close back. The back may be little wider than the stays and laced to the adjacent edges of the corset; or it may be introduced into the corset, as shown in Fig. 1, and the lacing-openings made at the side. Applied to the person, the springs *a a* stand one each side the spinal column, held in rigid position by the cross-connections *b*. The springs *a a* are curved vertically, corresponding to the natural curve of the back; but the adjacent sides of the two springs *a a*, being straight, serve not only to support the back, but also to support the spinal column in a straight vertical position, and thereby prevent or relieve curvature of the spine.

In inclosing the back or spinal springs, the fabric of that portion of the back which forms the outer and inner thickness, *e f*, of the corset

(see Fig. 4) should be such that the inner thickness may fall into the space between the two springs *a a*, as seen in Fig. 4, so as to permit 55 the spinal column to sink into that recess, in order that it may have the support of the springs from right to left to insure the retention or support of the spine in the proper vertical position. 60

The cut of the corset is immaterial to this invention—may be such as shown, or any other known or suitable cut—the essential feature of this part of my invention being the back-stay composed of two springs, *a a*, arranged substantially parallel to each other, and with the outwardly - curved transverse cross - connections *b*. 65

As a support for the shoulders, I introduce a steel (or other material) spring, *A*. (Seen detached in Fig. 5.) This spring is curved at its upper end to pass over the shoulder, and provided at its front end with a cushion, *h*, which will rest against the body of the person. The width of the spring is sufficient to lie easily 70 upon the shoulder. At the back, the spring extends down in a pocket in the corset, and about the waist-line is turned outward, as at *i*, forming a ledge-like projection, upon which the skirts of the wearer will rest, so that the 75 support of the skirts will come entirely upon the shoulder. This spring readily yields to the movement of the person, yet tends to hold the shoulders up and backward in their proper position, and will retain its place upon the 80 shoulder better than the usual flexible strap; and the support of the shoulder-brace is due to the elasticity of the spring and not to the drawing-strain of a strap around the shoulder. This shoulder-brace spring may be employed 85 in a corset independent of the back or spinal stay, and the spinal stay may be employed without this peculiar shoulder-spring. I therefore do not wish to be understood as limiting my invention to the combination in a corset of 90 this peculiar spinal stay and shoulder-spring; 95

What I do claim is—

1. A spinal stay for corsets, consisting of the two vertical springs *a a*, arranged substantially parallel with each other, and united by outwardly - curved transverse connections *b*, substantially as and for the purpose described. 100
2. A corset having in the central back-sec-

tion a spinal stay composed of two vertical springs, *a a*, united by transverse connections *b*, and so as to form a recess upon the inside of the corset between the said springs, substantially as described.

3. A corset having in the central back-section a spinal stay composed of two vertical springs, *a a*, united by transverse connections *b*, and so as to form a recess upon the inside of the corset between the said springs, with steel shoulder-springs *A*, introduced in pockets at the back of the corset, the upper end carried

over the shoulder, the lower end, *i*, turned outward to form a skirt-supporter, substantially as described.

4. A corset shoulder-spring, *A*, bent at its upper end to extend over the shoulder, and at the front provided with a cushion, *h*, its rear lower end, *i*, turned outward to form a skirt-supporter, substantially as described.

MAURICE F. LINQUIST.
